UNITED STATES PATENT OFFICE.

SIMON A. JAROSLAWSKI-FIORET, OF NEW YORK, N. Y.

TWIN-COMPACT VANITY CASE.

Application filed November 28, 1923. Serial No. 677,536.

To all whom it may concern:

Be it known that I, SIMON A. JAROSLAWSKI-FIORET, a citizen of Poland, and a resident of the city of New York, borough of Manhattan, in the county and State of New York, have invented a new and Improved Twin-Compact Vanity Case, of which the following is a full, clear, and exact description.

10 This invention has relation to vanity cases and has particular reference to an improvement in twin compact vanity cases.

15 The present invention contemplates a vanity case which is designed to respectively house rouge and powder compacts and which functions when open to expose both compacts simultaneously for use.

20 The outstanding object of the present invention resides in the provision of a vanity case in which the mirror supporting element is interposed between the two compacts for the purpose of separating the same when the case is in closed condition, whereby upon opening of the case the single mirror 25 will be conveniently arranged for facilitating the application of the rouge and powder.

As a further object the invention contemplates a twin compact vanity case in which the mirror supporting element having 30 hinged connection with one of the container sections operates, when swung to its closed position, to partially extend within both containers to serve as a means for frictionally maintaining the same in closed relation.

35 As a still further object the invention comprehends a vanity case of the character set forth which is comparatively simple in its construction and mode of operation, which is inexpensive to manufacture and 40 produce, and which is highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the 50 full extent indicated by the general meaning of the terms in which the claims are expressed.

In the drawings—

Figure 1 is a side view of a vanity case 55 constructed in accordance with the invention,

illustrating the container sections in partially opened relation.

Fig. 2 is a perspective view thereof in fully opened position.

Fig. 3 is a sectional view therethrough 60 taken on the line indicated at 3—3 in Fig. 2.

Fig. 4 is a fragmentary sectional view taken approximately on the line indicated at 4—4 in Fig. 3.

Referring to the drawings by characters of reference, 10 and 11 designate respectively a pair of compact container members or sections which are of substantially identical construction, shape and size. Each member or section includes a bottom 12 and a marginal upstanding flange 13, said flanges being provided with aligned hinge knuckles 14 at one side through which a hinge pin 15 extends to establish a hinged connection between the same whereby said sections may be swung to closed position with the free edges of the marginal flanges in contact, or to open position as illustrated in Figs. 2 and 3 whereby the members or sections are disposed alongside each other. 80

Within each section a compact retaining element 16 is arranged, which comprises a vertical flange or wall 17 and a horizontal flange or wall 18 at the upper end which is spaced below the free upper edge of the flange or wall 13 of the container members or sections. The section 10 has hingedly secured as at 19 to a point at right angles to its hinged connection with the section 11, 90 an intermediate member or section 20 which is of a shape and configuration similar to the sections and of a size to snugly fit within the open ends of the sections when the same are in closed relation. The member 20 is provided with a mirror retaining element 21 which secures the mirror 22 in place within the intermediate section 20. 95

The intermediate section is so connected with the outer section 10 that when the case is folded the intermediate section partially extends into the open end of each of the outer sections and frictionally engages with the same to retain said outer sections in relatively closed relation against casual opening movement. The horizontal wall or flange 18 further constitutes a shelf for engagement with the intermediate section whereby to limit the inward swinging movement of the same into the section 10. 105

The intermediate section has formed in its 110

outer side wall at a point diametrically opposite its hinge 19 a recess 23 for the insertion of the finger or thumb nail to facilitate the swinging of the same to open position.

5 The outer side wall of the intermediate section which is diametrically opposite the hinged connection between the sections 10 and 11 is provided with a catch lug or projection 24, while the inside of the flange 13 of the section 11 at the corresponding side is provided with a keeper depression 25 which is adapted to coact with the catch lug to form a catch or fastening means.

In use and operation when the case is in 15 closed condition the user swings the section 11 outwardly to a position alongside the section 10 as illustrated in Fig. 2. The intermediate section is then swung to the open position illustrated in Fig. 2 thereby exposing 20 the compacts which are arranged in the sections 10 and 11 for simultaneous use and whereby the single mirror 22 in the intermediate section 20 may be employed for applying the compacts to the face. When the 25 case is closed the intermediate section 20 serves effectually as a partition between the two compact container sections 10 and 11, in addition to functioning as a means for retaining the sections in closed relation.

30 I claim:

1. A vanity case comprising a pair of outer compact carrier sections each having an open end and a closed end hingedly connected at the open ends for contiguous 35 closed relation, an intermediate mirror carrying section hingedly connected to one of the outer sections and adapted when the case is closed to extend partially into the open end of each outer section for frictionally retaining said sections in closed relation, and means spaced inwardly from the open end of each of the outer sections constituting stops for engaging the opposite

sides of the intermediate section to limit the projection of the same into the ends of said outer sections.

2. A vanity case comprising a pair of outer compact carrier sections each having an open end and a closed end hingedly connected at the open ends for contiguous closed relation, an intermediate mirror carrying section hingedly connected to one of the outer sections and adapted when the case is closed to extend partially into the open end of each outer section for frictionally retaining said sections in closed relation, means spaced inwardly from the open end of each of the outer sections constituting stops for engaging the opposite sides of the intermediate section to limit the projection of the same into the ends of said outer sections, said means comprising a horizontal flange frictionally fitted within each outer section, and a vertical integral flange engaging the closed end of each outer section. 65

3. A vanity case comprising a pair of outer sections each having an open end and a closed end, a hinged connection therebetween at the open ends, an intermediate section hingedly connected to one of the outer sections, interengageable fastening means provided respectively on the remaining outer section and the said intermediate section, the intermediate section adapted when the case is closed, to partially extend into the 75 open end of each section for retaining said sections in closed relation, said outer sections constituting compact containers, and means within each outer section for retaining the compacts therein, said means engageable with the intermediate section for limiting the projection of said intermediate section into the open ends of the outer sections. 80

SIMON A. JAROSLAWSKI-FIORET.
